UNITED STATES PATENT OFFICE.

HUGH A. KENNEDY, OF NEWPORT, WASHINGTON.

BEARING FOR RIFLES.

Application filed September 7, 1922. Serial No. 586,685.

To all whom it may concern:

Be it known that I, HUGH A. KENNEDY, a citizen of the United States, residing at Newport, in the county of Pend Oreille and 5 State of Washington, have invented certain new and useful Improvements in a Bearing for Rifles, of which the following is a specification.

This invention relates to a bearing for 10 rifle cleaning rod, and has for its principal object, the production of a bearing which when associated with the cleaning rod will prevent the wear on the barrel of the gun being cleaned.

15 Another object of the invention is to provide a bearing of the above mentioned character, which can be easily inserted and removed from the barrel of the gun being cleaned which is adapted to receive a cleaning rod.

Another object of the invention is to provide a bearing of the above mentioned character, which is inexpensive to manufacture, simple in construction, strong and durable.

25 Other objects and advantages of this invention will become apparent during the course of the following description.

In the accompanying drawings forming a part of the description, and in which like 30 numerals designate like parts throughout the several views.

Figure 1 is a central longitudinal section of the invention showing the bearing as applied within the barrel of the gun and the 35 cleaning rod passing through the bearing,

Figure 2 is a sectional view taken on the line 2—2 of Fig. 1, and

Figure 3 is a perspective view of the bearing.

40 In the drawing, wherein for the purpose of illustration is shown the preferred embodiment of my invention, the numeral 1 designates a barrel of any well known type of rifle or gun. Adapted to be inserted in 45 the forward end of the barrel 1 of an ordinary rifle is a bearing 3. This bearing 3 consists of an elongated sleeve 4, which is adapted to extend into the barrel of the gun a substantial distance as shown in Fig.

50 1 in the drawings, for a purpose hereinafter to be fully described. The exterior face of the opposite end of the sleeve is tapered as at 5 and has a flange 6 provided at its outer end. The bearing 3 is provided with a 55 smooth longitudinally extending bore 7 for the purpose of receiving a cleaning rod 8.

In use, the bearing 3 is placed in the barrel of the gun so that the elongated portion 4 of the bearing extends within the barrel a substantial distance. This may be accomplished by hitting on the flange portion 6 formed on the outer end of the bearing. The bearing 3 by having its exterior face tapered presents an enlarged outer end for centering the inner end of the sleeve within the barrel and further aids in holding the bearing 3 within the barrel of the gun. After the bearing 3 has been inserted in the barrel of the rifle or gun, a cleaning rod 8 is then passed through the longitudinally extending bore 7 of the bearing and it will thus be seen that a free reciprocating motion of the cleaning rod may be easily had. Of course, any suitable material may be placed on the end of the cleaning rod to further aid in the cleaning of the barrel of the gun, and it is not thought that it is necessary to show this feature in the present invention.

Ordinarily when a barrel of a gun or 80 rifle is to be cleaned, the person takes the cleaning rod and merely inserts the same within the barrel of the rifle and rotates and reciprocates the same in order to clean the barrel, and in so doing causes the barrel of the gun to be worn by the cleaning rod rubbing against the face of the barrel during the cleaning operation. By providing a bearing of the above mentioned character it will be seen that the wearing out 90 of the barrel of the gun or rifle is done away with and the barrel may be more readily and easily cleaned.

The bearing used in the present invention may be made of any suitable material preferably brass, but I do not wish to confine myself to any particular material.

It is to be understood that the form of my invention herewith shown and described is to be taken as the preferred example of 100 the same, and various changes in the shape, size and arrangement of parts may be resorted to without departing from the spirit of the invention and the scope of the subjoined claim.

105 Having thus described my invention what I claim is:—

As a new article of manufacture, a device for facilitating the cleaning of gun barrels comprising a frusto-conical-shaped centering member for engaging the bore of the gun barrel, an elongated cylindrical bearing

sleeve of the same diameter throughout its length formed on the tapered end of the centering member, the centering member and the elongated bearing sleeve having plain 5 outer surfaces and a smooth longitudinally extending axially disposed gun cleaning rod receiving bore, and an annular flange formed on the enlarged end of the centering member for forming an anvil for facil-

tating the placing of the device in a gun barrel.

In testimony whereof I affix my signature in presence of two witnesses.

HUGH A. KENNEDY.
